(57) **CLAIM**

The ornamental design for a hair dryer toy, as shown and described.

DESCRIPTION

FIG. 1 is a front, right and top perspective view of a hair dryer toy, showing my new design;

FIG. 2 is a rear, left and bottom perspective view thereof;

Fig. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front view thereof, shown in a condition of use; and,

FIG. 10 is another front view thereof, shown another condition of use.

The broken lines shown in the drawings illustrate portions of the hair dryer toy that form no part of the claimed design.

1 Claim, 10 Drawing Sheets
